DOOR OPERATING MECHANISM.

No. 603,895.

Patented May 10, 1898.

UNITED STATES PATENT OFFICE.

AUGUST DITTMAR, OF LAWRENCE, OHIO.

DOOR-OPERATING MECHANISM.

SPECIFICATION forming part of Letters Patent No. 603,895, dated May 10, 1898.

Application filed December 16, 1897. Serial No. 662,105. (No model.)

To all whom it may concern:

Be it known that I, AUGUST DITTMAR, a citizen of the United States, residing at North Lawrence, in the county of Stark and State of Ohio, have invented a new and useful Door-Operating Mechanism, of which the following is a specification.

My invention relates to improved mechanism for operating mine-doors, being particularly applicable to sliding doors; and it has for its object the production of simple mechanism which may be automatically operated by a car passing into or out of the mine.

The invention will first be described with reference to the accompanying drawings and then pointed out in the claims.

Figure 1 of the drawings is a perspective view illustrating the application of my invention, the doors being shown closed. Fig. 2 is a view in elevation of the same, showing a car in proper relative position and the doors open. Fig. 3 is a plan view of the same, the doors being closed. Fig. 4 is a detail illustrating the manner of accommodating the rock-shaft to a curved track. Fig. 5 is a view in elevation of the rock-shaft bearing, the shaft being in section. Fig. 6 is a perspective view of the coupling-box for the rock-shaft. Fig. 7 is a sectional view of the same, showing the weight-lever in place to illustrate its adjusting feature.

Referring to the drawings, A represents the rails of a track leading into the mine, secured to ties 1, and B the doors, preferably mounted to slide upon hangers 2, the doors being mounted in the usual framework, comprising sills 3, uprights 4, and cross-pieces 5, all as shown.

Alongside one rail A, I locate a rectangular operating-bar 6, set on edge, as shown, the bar normally projecting above the tread of the rail and being of sufficient length to extend a suitable distance on each side of the doors.

C represents a rock-shaft mounted in bearings c, hereinafter described, it being preferably square in cross-section and adapted to rock on edge. The bearings c are conveniently secured upon the ties 1, as shown, and comprise a base-plate 7, having an obtuse-angled depression 8 therein, and a cap 9 for the base-plate, having an upwardly-extending re-

cess 10, adapted to receive the upper portion of the rock-shaft, the portion of this recess that contacts with the edge of the rock-shaft being cut on an arc similar to the arc formed by the upper edge of the shaft in movement, thus holding the rock-shaft in place and yet permitting the necessary rocking movement, all as clearly shown in Fig. 5. The rock-shaft is preferably formed in three or more lengths and secured together end to end by what I term "coupling-boxes" 11, these boxes comprising two plates having laterally-extending bosses 12, in which the ends of the rock-shaft are secured by set-screws 13, the plates comprising the boxes being then secured together by screws 14, thus forming practically a continuous rock-shaft.

D represents weight-levers, their inner ends being turned at a right angle and securely bolted to the operating-bar 6, as shown, the levers passing through the coupling-boxes 11 and being held therein by the screws 14. Each lever is longitudinally adjustable with relation to the box through slots 15, formed in the lever and through which the screws 14 pass, all as clearly shown in Fig. 7. Weights 16 are adjustably secured on the ends of levers D by set-screws 17.

E represents an angle-lever secured on the rock-shaft close to the doors B, the inner end of this lever being secured to the operating-bar 6, while its outer end is secured to the short arm of a lever 18 by a link 19, the lever 18 being pivoted in a standard 20, secured in the door-frame. The long arm of lever 18 is connected to one door B by a link 21, the extreme end of the lever being pivoted to one end of a rod 22, the other end of which rod is connected to the longer arm of another lever 23, pivoted to a standard 24, rising on the opposite side of the door-frame, the lower end of lever 23 being connected to the other door B by a link 25. The upper portion of lever 23 is bent, as shown, to avoid obstructing the passage-way through the doors when the latter are open.

By forming the weight-levers D with slots 15, through which the screws 14 pass for securing the plates of the coupling-boxes together, I am enabled to adapt the mechanism for a track having a curve without bending the rock-shaft, as the slots permit the longi-

tudinal adjustment of the levers in the boxes, allowing the track and the operating-bar 6 to be moved nearer to or farther from the rock-shaft without disturbing the latter, as will be 5 clearly seen in Fig. 4.

The operation of my invention will be clear from the above description taken in connection with the drawings, it being seen that a car E, advancing upon the rails A, rides upon 10 and depresses the operating-bar 6, which through the various lever mechanism operates to open the doors, the weight-levers D causing a reversal of this operation and closing the doors when the car has passed off the bar 6.

15 Having thus described my invention, what I claim as new, and desire to secure by Letters Patent, is—

1. The combination, with the track and the doors above the track, of a rock-shaft formed 20 in a plurality of lengths and secured together by coupling-boxes, lever mechanism connecting the doors and rock-shaft, means for operating the rock-shaft in one direction to open the doors, and weight-levers for operating the 25 rock-shaft in the opposite direction for closing the doors, said weight-levers passing through the coupling-boxes and being longitudinally adjustable therein, as and for the purposes stated.

30 2. The combination, with the track and the doors above the track, of an operating-bar alongside the track, a square rock-shaft alongside the track and connected to the operating-bar, bearings for the rock-shaft in which the

latter is adapted to rock on edge, said bearings comprising a base-plate having an angular depression the meeting surfaces of which are at a greater angle than the meeting surfaces of the rock-shaft and a cap removably secured to the base-plate, the portion of said 40 cap coming into contact with the edge of the rock-shaft being on an arc similar to the arc of the upper edge of the rock-shaft in movement, lever mechanism connecting the rock-shaft and doors, and weight-levers secured to 45 the rock-shaft and to the operating-bar.

3. The combination, with the track and the doors above the track, of a rock-shaft alongside the track, an operating-bar adjacent to one rail of the track, an angle-lever secured 50 to the rock-shaft and connected at one end to the operating-bar, a lever pivoted in the door-frame and having its lower end connected to the angle-lever, its upper end being connected to one of the doors, another lever also pivoted 55 in the door-frame opposite the first lever and having its lower end connected to the remaining door, and a horizontal bar connecting the upper ends of said levers, substantially as and for the purposes stated. 60

In testimony that I claim the foregoing as my own I have hereto affixed my signature in presence of two witnesses.

AUGUST DITTMAR.
